UNITED STATES PATENT OFFICE

98,147

DESIGN FOR A BUCKLE OR SIMILAR ARTICLE

David Cooper, Brooklyn, N. Y.

Application November 4, 1935, Serial No. 59,370

Term of patent 3½ years

To all whom it may concern:

Be it known that I, David Cooper, a citizen of the United States, residing at 3115 East 4th Street, Brooklyn, in the county of Kings, State of New York, have invented a new, original, and ornamental Design for a Buckle or Similar Article, of which the following is a specification, reference being had to the accompanying drawing, forming part thereof.

my new design.

I claim:

The ornamental design for a buckle or similar article as shown.

DAVID COOPER.
